APPARATUS FOR THE PRODUCTION OF
ARTIFICIAL FILAMENTS AND LIKE MATERIALS

Henry Dreyfus, London, England

Application May 2, 1933, Serial No. 668,926
In Great Britain May 19, 1932

4 Claims. (Cl. 18—8)

This invention relates to apparatus for the manufacture of artificial materials, and is particularly concerned with improvements in the spinning jets or nozzles used in the production 5 of artificial filaments or like extruded products. The invention is of particular importance in connection with the spinning of filaments at high speeds and the spinning of fine filaments, whether at high speeds or otherwise.

10 Spinning jets for the production of artificial filaments are usually and most conveniently made of sheet metal, pressed or otherwise formed into the shape of a shallow cup, the flat bottom of which is pierced with orifices for the extrusion of 15 the filaments. A spinning solution is supplied inside the jets under pressure, and is thereby forced through the orifices to form the filaments, the faster the required rate of extrusion and the finer the orifices the higher being the pressure 20 which must be applied to the spinning solution behind the face of the spinning jet. In spinning at high speeds therefore, and especially in the spinning of fine filaments the pressure behind the jet may be so high as to cause the jet to bulge 25 outwardly. The phenomenon of jet bulging gives rise to many difficulties. Thus for example, in a bulged jet, the spinning orifices point outwards and cause the extruded filaments to spread instead of proceeding as a parallel compact bundle. It is an object of the present invention to 30 reduce or overcome the difficulties outlined above, by reducing or preventing the bulging of the jets.

According to the present invention, a sheet metal jet for the purpose of spinning is thickened 35 locally over areas not occupied by the spinning orifices, with the result that the sheet metal is reinforced and the tendency to bulging is reduced or avoided. At the same time the metal through which the orifices are bored is not increased in thickness, with the result that the 40 length of the passages is not increased, a factor of some importance, not only bearing upon the pressure necessary to force the spinning solution through the orifices, but also having its effect on 45 the nature of the thread produced.

It is preferable that the metal of which the jet consists should be thickened in lines which run generally in radial directions, thus affording the greatest reinforcement against bulging. If 50 desired, however, one or more circles of thickened metal concentric with the jet face may be employed in conjunction with the radial lines so formed, such circles helping to reinforce the jet between the radial lines. Thus, for example, 55 it is a convenient practice to arrange the spin-

ning orifices in a circle on the face of the jet, and such a jet may be strengthened by a circle of thickened metal inside and/or outside the circle of filaments and by radial ribs, which ribs may, if desired, terminate in a circle or boss 5 within the circle of orifices.

The thickening of the sheet metal in the manner described above may be effected by any convenient method. Thus, for example, the sheet metal of which the jet is to be formed may be 10 stamped or pressed, so that the desired pattern of thickened portions is produced, and such stamping may be effected at any convenient stage, but preferably before the boring of the orifices, which may be subsequently formed in the thin 15 part of the metal.

The invention is of especial advantage in its application to jets having a large number of orifices, such as are usually employed in the spinning of fine filaments. The great number of 20 orifices requires a greater area of jet face, and this results in an increased tendency of the jet to distort, especially where the orifices themselves are of small size and so necessitate a greater extrusion pressure. Further, the greater 25 distance of the orifices from the centre of the jet resulting from the larger area of the jet face occupied by the orifices, increases the spreading of the filaments as they issue from the orifices. Again, jets of large face area may be used in 30 order to accommodate a large filter member immediately above the jet, as is of especial importance in high speed spinning. These jets are apt to distort to a greater extent than jets of small face area, irrespective of the number, size 35 or position of the orifices. While both the size of the jet face and that of the circles of orifices may be reduced as far as possible in such cases, the present invention is nevertheless of particular 40 advantage when the extent to which such reduction can be carried out is limited.

While the spinning jet according to the present invention is applicable generally to the production of artificial filaments by extrusion, whether 45 by the wet or coagulation method as usually employed in the spinning of viscose or cuprammonium filaments, or by the dry or evaporative method, as usually employed in the spinning of filaments of cellulose acetate or other organic 50 derivatives of cellulose, the invention is especially useful in the production of filaments by the dry or evaporative method because of the high spinning speed and high concentration of spinning solution generally adopted in this method of 55

spinning and the resultant higher pressures on the jets.

Some specific forms of jet according to the invention will now be described by way of example with reference to the accompanying drawing, in which:—

Figure 1 is an elevation in half section of a nozzle assembly embodying one form of spinning jet;

Figures 2 and 3 are a plan and sectional elevation respectively of the spinning jet shown in Figure 1; and

Figures 4 and 5 are views similar to Figures 2 and 3 of a further form of jet according to the invention.

Referring to Figure 1, a pipe 7 for the supply of spinning solution is provided at its lower end with a connecting piece 8 which is cut with screw threads 9 on its periphery and has a machined face 10. A large nut 11 is screwed on to the piece 8 in order to secure against the face 10 a filter 12 and a spinning jet 13. It will be noted that the connecting piece 8 expands to a relatively large diameter and that the filter 12 and jet 13 are consequently of large area.

As shown in greater detail in Figures 2 and 3, the jet 13 comprises a securing flange 14 and a face 15 in which are bored two concentric circles of orifices 16, 17. Inside the inner circle of orifices 17, the thickness of the jet is increased to form a boss 18 from which four ribs of thickened metal 19 run radially outwards to the edge of the face 15. Outside the inner circle of orifices 17 and inside the outside circle 16 is a circle of thickened metal 20 concentric with the face 15 and running into the ribs 19. The ribs 19 divide the orifices 16, 17 of each circle of orifices into four quadrants, no orifices being bored through the thickened metal of the ribs 19. The provision 40 of the ribs 19 provides a strong resistance against the bulging of the jet due to the pressure of spinning solution being forced through the orifices 16, 17. Further reinforcement is provided by the boss 18 and circle 20. By reinforcing the jet in this manner, the area of the jet, and in consequence the number of orifices which may be bored therein is considerably increased. The thickening of the jet is formed on the inside of the jet, so that the outside face remains smooth so as 50 to be easily cleaned when necessary.

It will be understood that, in the drawing, the thickness of the metal of which the jet is formed

is exaggerated for the purpose of clarity. A suitable thickness for the unthickened portions of the jet is about .01", while the thickened portions may be increased to any desired extent, e. g. from .02" to .1" or more. Likewise, the size of 5 the orifices is much exaggerated.

In Figures 4 and 5, a spinning jet is shown having a single circle of orifices 23. The face 15 of the jet is reinforced with six radial ribs 26 dividing the circle 23 into six parts. The ribs 10 26 originate from a circle 27 of thickened metal inside the circle of orifices 23, and a further circle 28 of thickened metal is provided outside the circle of orifices. As in the jet shown in Figures 2 and 3, the ribs 26 and the circles 27 and 28 15 reinforce the face 15 of the jet against bulging.

What I claim and desire to secure by Letters Patent is:—

1. A spinning jet for the production of artificial filaments, yarns, threads or the like, said jet having a face of thin metal provided on the inside of said face and integral therewith, over areas not occupied by spinning orifices with lines of increased thickness adapted to reinforce said face, the outer face of said jet being left smooth 25 to facilitate jet wiping.

2. A spinning jet for the production of artificial filaments, yarns, threads, or the like, said jet having a face of thin metal provided on the inside of said face and integral therewith, over areas 30 not occupied by spinning orifices, with radial lines of increased thickness adapted to reinforce said face, the outer face of said jet being left smooth to facilitate jet wiping.

3. A spinning jet for the production of artificial filaments, yarns, threads or the like, said jet having a face of thin metal provided on the inside of said face and integral therewith, over areas not occupied by spinning orifices, with circles of increased thickness concentric with said 40 face and adapted to reinforce said face, the outer face of said jet being left smooth to facilitate jet wiping.

4. A spinning jet for the production of artificial filaments, yarns, threads or the like, said jet 45 having a face of thin metal provided on the inside of said face and integral therewith, over areas not occupied by spinning orifices with radial lines and circles of increased thickness adapted to reinforce said face, the outer face of said jet 50 being left smooth to facilitate jet wiping.

HENRY DREYFUS.
